UNITED STATES PATENT OFFICE.

CLYDE W. MUMMERY, OF DETROIT, MICHIGAN.

OIL BURNER.

Application filed November 23, 1921. Serial No. 517,229.

To all whom it may concern:

Be it known that I, CLYDE W. MUMMERY, a citizen of the United States, residing at Detroit, in the county of Wayne and State 5 of Michigan, have invented certain new and useful Improvements in Oil Burners, of which the following is a specification.

This invention relates to oil burners of the wickless type, especially suitable for 10 burning kerosene, and in which the combustible vapor is generated after starting, by means of heat communicated to the walls of a generating chamber or trough above which is a pair of inner and outer shells 15 which are perforated to supply air to the mixture and the flame.

The object of the present invention is to simplify and cheapen the structure of such a burner. A further object is to provide 20 improved means for supplying air to the mixture, this air being heated to assist in vaporization. A further object is to provide improved means for supplying air to the flame at or about the point of combustion.

25 Further objects and advantages will appear from the following description and the accompanying drawings in which Fig. 1 is a vertical section of the burner. Fig. 2 is a section on the line 2—2 of Fig. 1.

30 Referring specifically to the drawings, 6 indicates an oil supply pipe controlled by a suitable valve 7. This pipe discharges through an opening 8 into the base of the burner which consists of a trough 9 which in 35 the form shown is annular, the trough being substantially V-shaped in cross section, and above the oil line the inner and outer walls or sides of the trough are provided with air holes 10 and 11 to admit a suitable 40 amount of air into the trough above the oil therein.

Upon the top of this trough rests the burner body which consists principally of two concentric tubular shells, the inner one 45 being indicated at 12 and the outer one at 13. These rest on opposite edges of the trough and form a mixing and combustion chamber therebetween. The inner shell 12 is closed at the top as indicated at 12^a, and 50 the mixing and combustion space 14, between the shells, is open at the top. Each of the shells 12 and 13 has a large number of small holes 15 through the same, through 55 which holes air is drawn into the space 14 where it mixes with the vapor raising from the trough below. The outer shell 13 is

surrounded by a thin metal casing 17 which depends from the flaring lip or rim of the shell, and the casing 17 is open at the bottom so that air may enter within the same 60 where it is heated before being supplied to the combustion space. Near its upper end the shell 13 has a row of relatively large holes 18, and also, near its extreme end or upper edge has a row of similar holes 19, 65 and air will flow through these holes to the flame at the top of the combustion space.

The pipe 6 is threaded into a hollow boss 20 and extending vertically through and across the chamber in this boss is an air 70 pipe 21. This pipe is open at the bottom as indicated at 22 but is closed at the top by a cap 23. It projects upwardly into the space between the shell 13 and the casing 17 and is preferably located in contact with 75 the former so that it will conduct heat therefrom. In the chamber of the boss 20 the pipe has a plurality of holes 24 located slightly above the oil line or level and arranged to discharge heated air into the boss. The 80 outer wall of the trough 9 has a circular downwardly inclined flange 25 at its rim which assists in directing the air toward or into the holes 11.

In operation, the burner may be started 85 with gasoline or alcohol by pouring a small amount into the trough and lighting the same, and the flame from the gasoline or alcohol will create heat enough to start the generation of the oil which is admitted into 90 the trough from the pipe 6. As the burner becomes heated, the air in the pipe 21 will flow or be drawn through the holes 24 in said pipe into the chamber in the boss, and this air mixes with the vaporized oil, the 95 point of vaporization being within the chamber of the boss 20. The air is drawn in by the suction of the flame between the burner shells 12 and 13, and the mixture, including unvaporized oil if any, flows 100 through the hole 8 into the trough where the vaporization is completed and the vapor burns between the shells 12 and 13 and at the top thereof, additional air being supplied through the holes in the shells as well 105 as through the large holes 18 and 19 at the top. Any air not necessary for immediate combustion will flow through the holes 19 around the outside of the flame.

A burner so constructed will generate 110 and burn kerosene without smoke or odor, producing a blue flame of high heating

quality, without requiring the use of a wick. The burner shells can be readily lifted off the base trough to permit cleaning of the latter if and when necessary.

5 I claim:

1. A burner comprising a lower trough, and spaced perforated shells standing thereon, an inlet oil chamber discharging into the trough, and means to supply heated air 10 to said chamber.

2. A burner comprising a lower oil trough, spaced perforated shells standing thereon, a hollow inlet chamber discharging into the trough, and an air pipe standing beside one 15 of the shells and having discharge opening into said chamber.

3. A burner comprising a lower oil trough, spaced perforated shells standing thereon, a hollow inlet chamber discharging into the 20 trough, and an air pipe standing beside one of the shells and having discharge openings into said chamber, the lower end of said pipe extending across said chamber and being provided with said openings therein.

25 4. A burner comprising a lower oil trough, a pair of spaced perforated shells standing thereon, an oil supply chamber opening into

the trough, and an air pipe extending across said chamber and standing beside one of the shells, said pipe being open at the bottom and closed at the top, and having holes opening into said chamber. 30

5. A burner comprising a lower generating trough, inner and outer spaced shells standing above said trough, said shells having a plurality of small holes through the same, the outer shell being flared at the top, said flared portion having a row of larger openings. 35

6. A burner comprising a generating 40 trough, a pair of spaced perforated concentric shells standing above the same, the outer shell being flared at the top, and having a row of relatively large holes at the top of the space between the shells, and 45 having another row of relatively large holes near the outer edge of the flared part thereof.

In testimony whereof, I affix my signature in presence of two witnesses.

CLYDE W. MUMMERY.
